United States Patent

Des. 236,703
Patented Sept. 9, 1975

236,703

ALL-TERRAIN VEHICLE

Dwight C. Baker, 19633 SE. 29th St., Issaquah, Wash.
98027, and Arpad P. Augusztiny, 7603 S. Sunnycrest
Road, Seattle, Wash. 98178

Filed Dec. 3, 1973, Ser. No. 421,313

Term of patent 14 years

Int. Cl. D12—14

U.S. Cl. D12—1

Fig. 1

Fig. 2

Fig. 3

Fig. 4

FIG. 1 is a side elevational view of an all-terrain vehicle showing our new design, it being understood that the opposite side is a mirror image thereof;

FIG. 2 is a top plan view thereof;

FIG. 3 is a front elevational view thereof; and
FIG. 4 is a rear elevational view thereof.

We claim:

The ornamental design for an all-terrain vehicle, as shown and described.
